UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FEELER LOOM.

Application filed May 26, 1917. Serial No. 171,129.

To all whom it may concern:

Be it known that I, JONAS NORTHRUP, a citizen of the United States, residing at Hopedale, in the county of Worcester and State of Massachusetts, have invented certain new and useful Improvements in Feeler Looms; and I do hereby declare the following to be a full, clear, and exact description of the invention, such as will enable others skilled in the art to which it appertains to make and use the same.

The present invention relates to an improvement in feeler looms, and more particularly the invention relates to an improvement in thread extracting devices for such looms.

Feeler looms are a type of automatic weft replenishing looms wherein the weft replenishing mechanism operates to insert a fresh supply of filling in the active shuttle when the old filling is exhausted to a predetermined extent, as determined by the filling feeler mechanism. These looms are usually constructed with the weft replenishing mechanism located on one side of the loom and the filling feeler mechanism located on the opposite side of the loom. As a result of this construction, the indication of critical or predetermined exhaustion of the filling by the filling feeler mechanism takes place on what is known as the filling feeling beat-up of the lay, and the weft replenishing operation takes place on the next succeeding or replenishing beat-up of the lay. On the replenishing beat-up of the lay, the usual feeler thread parter mechanism is thrown into operation to sever the filling end extending from the selvage to the bobbin about to be ejected from the shuttle. The severed filling end, which is known as the outgoing filling end, or simply as the filling end, is then usually pulled through the shuttle eye by the ejected bobbin as it falls into a receptacle or can provided for the purpose. It occasionally and even frequently happens, however, that the outgoing filling end is caught between the shuttle and the binder or the front wall of the shuttle box, and held thereby, so that, as the ejected bobbin falls, it does not pull the filling end through the shuttle eye. Consequently, when the shuttle evacuates the shuttle box on its first pick after the replenishing operation, it often draws the filling end toward the shed, and sometimes into

the shed, where, if it is allowed to remain, there results a double pick and consequent blemish in the cloth.

It has been proposed heretofore to eliminate these double picks by providing feeler looms with thread extracting devices. Some of these devices have operated to attempt to pull the outgoing filling end through the shuttle eye while the shuttle is still in the replenishing shuttle box; and some of these devices have operated to pull the outgoing filling end out of the shed, before the closing thereof, immediately following the first pick of the shuttle after the replenishing operation.

The object of the present invention is to produce a thread extracting device which will engage the outgoing filling end as the shuttle evacuates the replenishing shuttle box on the first pick after the replenishing operation, and hold the filling, so that, as the shuttle evacuates its box, the movement of the shuttle relatively to the filling will cause the filling to be pulled through the shuttle eye. To the accomplishment of this object, and such other objects as shall hereinafter appear, the present invention consists in the structure described in the following specification and particularly pointed out in the appended claims.

The preferred form in which it is contemplated embodying the present invention is illustrated in the accompanying drawings, in which Figure 1 is a side elevation of a portion of a feeler loom showing the application of the thread extracting device of the present invention thereto; Fig. 2 is a front elevation of the parts shown in Fig. 1; Fig. 3 is a top plan of the replenishing shuttle box, on an enlarged scale, showing the application of the thread hook of the thread extracting device thereto; and Fig. 4 is a view illustrating the action of the thread extracting device.

The feeler loom to which the thread extracting device of the present invention is applied may be of any usual or preferred form. The loom, a portion of which is illustrated in the drawings, comprises a filling feeler mechanism located on one side of the loom, and a weft replenishing mechanism located on the other side of the loom, these mechanisms being connected by a rock or change shaft 8 which is journaled in brackets

on the front of the loom and extends transversely thereof. When the filling feeler mechanism indicates that the running filling has approached the point of predetermined or critical exhaustion, the rock shaft 8 is turned in a clockwise direction, viewing Fig. 1, so that on the next succeeding or replenishing beat-up of the lay the critically exhausted bobbin 9 may be forced out of the shuttle 10 and a filled bobbin be inserted in its place. As the lay beats up on its replenishing beat, the usual feeler thread parter, located near the replenishing mechanism, engages the filling end extending from the selvage to the outgoing bobbin and severs it. Then, when the replenishing operation takes place, the ejected bobbin 9 falls through the aperture 11 cut in the replenishing shuttle box 12 and falls against the bobbin chute 14 and is deflected thereby into its receptacle.

The bobbin chute 14 is pivotally mounted so that it may be tilted into and out of operative position under the replenishing shuttle box 12. During regular weaving the tilting bobbin chute is held in inoperative position, as shown in dotted lines in Fig. 1, and on the indication of predetermined exhaustion of the running filling, the bobbin chute is tilted rearwardly into operative position so as to be under the replenishing shuttle box 12, on the next forward beat of the lay when the replenishing operation takes place. The operative position of the bobbin chute is shown in full lines in Fig. 1, and is determined by a stop lug 13. The bobbin chute is loosely mounted for its tilting movements on a stud 15 extending outwardly from the end 16 of a bracket 17 adjustably secured by means of a bolt 18 to the loom frame 19. The stop lug 13 is conveniently fixed on the bracket 17.

The bobbin chute receives its actuation into and out of operative position from the rock shaft 8. The connections between the rock shaft 8 and the bobbin chute consist of an arm 21 secured to the rock shaft and extending downwardly and rearwardly therefrom, and a link 22 which is pivotally connected at 23 with the bobbin chute and is articulated with the free end of the arm 21 by means of a pin and slot connection 24 and by means of a spring 25. This pin and slot and spring connection between the arm 21 and link 22 is for the purpose of preventing breakage of parts, in case a bobbin should be caught between the bobbin chute and the lay 27 as the latter beats back after the replenishing operation. It will be observed from an inspection of Fig. 1, that the arrangement of the connections between the link 22 and the arm 21 is such that the bobbin chute is positively actuated into operative position and is yieldingly actuated into inoperative position. It is this yielding actuation of the bobbin chute into inopera-

tive position which obviates the breakage of parts, inasmuch as it permits the rock shaft and the arm 21 to return to normal position without exerting their positive actuation upon the bobbin chute.

In order that the falling bobbin may attempt to pull the outgoing filling end from the shuttle eye, it is desirable that the bobbin should fall tip first. If the bobbin falls butt first, the filling remaining thereon will naturally unwind as the bobbin falls, so that the part extending through the shuttle eye is not so likely to be pulled therethrough. By making the bobbin fall tip first, the bobbin is caused to exert as great a pull as possible upon the outgoing filling end, and this pull will be generally sufficient to extract the filling end out of the shuttle box, unless it is firmly caught between the side of the shuttle and the front wall or binder of the shuttle box. The means employed in the present invention for causing the bobbin to descend tip first is a bobbin engaging lug 28 projecting forwardly from the upper and outer end of the bobbin chute and located, when the bobbin chute is in operative position, in the path of fall of the bobbin tip. The force with which the critically depleted bobbin is forced out of the bobbin holding jaws of the shuttle is such that when the tip of the bobbin strikes the bobbin engaging lug 28, the butt end of the bobbin in its rapid descent swings under the tip engaging lug so that the bobbin tip describes a semi-circle, and thereupon the bobbin continues its descent tip first, as shown in Fig. 2. And so, the filling is temporarily prevented from unwinding from the bobbin, and consequently, unless the upper end of the filling is caught in the shuttle box, it will be pulled through the shuttle eye.

In case the outgoing filling end is caught between the side of the shuttle and the front wall or binder of the shuttle box, the present invention provides means to cooperate with the tilting bobbin chute to cause the filling end to be engaged and held, so that, as the shuttle evacuates the replenishing shuttle box on its first pick after the replenishing operation, the caught filling end will not be drawn toward the shed, and therefore cannot enter the shed. The means illustrated in the drawings for cooperating with the tilting bobbin chute for accomplishing this purpose, comprises a thread hook 30 secured by a bolt 31 to the picker stick check post 32. The shank portion 33 of the hook lies flat against the under side of the front of the replenishing shuttle box 12, and on its inner end it is provided with a downwardly projecting thread engaging barb 35. As the shuttle evacuates the replenishing shuttle box, the filling is drawn against the inside of the barb and held thereby.

The operation of the thread extracting

device of the present invention in pulling the outgoing filling end out of the shuttle eye and thereby preventing it from entering the shed, is as follows: It is assumed that the loom is performing its regular operation of weaving cloth and that the shuttle is regularly paying out filling into the shed, until the filling becomes exhausted to a predetermined extent. Thereupon the filling 6 feeler mechanism indicates the predetermined exhaustion of the filling and causes the rock shaft 8 to be oscillated clockwise, viewing Fig. 1, so as to positively move the tilting bobbin chute 14 into operative position, so that, by the time the lay reaches its front center on the replenishing beat-up, the bobbin chute will be under the replenishing shuttle box. Previous to the replenishing operation, the thread parter mechanism severs the filling extending from the selvage to the outgoing bobbin. The replenishing operation now takes place and the critically exhausted bobbin 9 is ejected from the shuttle. The force of the ejection is such that when the tip of the bobbin strikes the lug 28, the bobbin swings around and descends tip first. It is assumed that the outgoing filling end has been caught between the shuttle and the shuttle box, and that, consequently, as the bobbin falls it does not pull the outgoing filling end through the shuttle eye. Of course when the filling end is caught, it unwinds from the bobbin, which descends into its receptacle before the thread extracting operation can take place. But this does not in any wise affect the thread extracting operation. The weft replenishing operation having been completed the lay beats backwardly, and 10 synchronously therewith the rock shaft 8 returns to normal position and draws the outgoing bobbin chute forwardly. By the time the lay has reached its top center, which is one-half of its backward beat, the tilting bobbin chute has reached to one-half of its return movement. The relative positions of the lay and the bobbin chute at this time are illustrated in Fig. 4. The shuttle is now picked to the opposite side of the loom, and inasmuch as the shuttle eye is toward 15 the front of the loom and the outgoing filling end extends through it down past the front side of the tilting bobbin chute, as shown in Fig. 4, the filling will be drawn against the inner side of the barb 35 of the thread extracting hook 30, and will be held thereby as the shuttle evacuates the shuttle box. It will have been observed from a consideration of this description, with reference to the drawings, that it is the cooperative action between the downwardly projecting barb 35 and the tilting bobbin chute which effects the extraction of the outgoing filling end from the shuttle as the shuttle 20 leaves its shuttle box. It is seen, there-

fore, that there is no attempt of the parts to pull the filling end out of the shuttle while the shuttle still remains in the shuttle box, except by the action of the descending bobbin. Dependence is first placed on the falling bobbin to extract the filling end from the shuttle, and if this fails, then the cooperative action between the tilting bobbin chute and the thread hook successfully completes the thread extraction, effectually preventing the outgoing filling end from being drawn into the shed. 70

The preferred form in which it is contemplated embodying the invention has been described in the foregoing specification and illustrated in the accompanying drawings. It will be understood, however, that the invention may be embodied in other forms than that shown and described, without departing from the spirit of the following claim: 80

Having thus described the invention, what is claimed as new is:

1. A thread extracting device for automatic looms having, in combination, a rock shaft, a tilting bobbin chute, connections between the rock shaft and the bobbin chute whereby the latter is held in inoperative position during regular weaving and moved to operative position upon an oscillation of the rock shaft, and a thread hook on the lay, the tilting bobbin chute being constructed and arranged to engage a filling end extending from the ejected bobbin through the shuttle eye, and upon being tilted back into its inoperative position to positively carry the filling to the mouth of the thread hook to effect a positive engagement therewith. 90

2. A thread extracting device for automatic looms having, in combination, a rock shaft, a tilting bobbin chute, yielding connections between the rock shaft and the bobbin chute arranged so that the chute is positively moved into operative position and yieldingly moved into inoperative position, and a thread hook to cooperate with the bobbin chute while the latter is moving into inoperative position to engage a filling end extending from an ejected bobbin up through the shuttle eye. 100

3. An automatic loom having, in combination, a shuttle box, a bobbin chute beneath the shuttle box, and a lug on the bobbin chute in position to be engaged by an ejected bobbin, the lug being arranged to extend only a short distance down the bobbin chute to thereby permit the butt of the bobbin to swing thereunder without restriction as a result of the impact of the tip with the upper surface of the lug, to thereby permit the bobbin to thereafter descend tip first. 110

4. An automatic loom having, in combination, a rock shaft, a lay, a shuttle box on the lay, a tilting bobbin chute normally in inoperative position, connections between 120

125

the rock shaft and the bobbin chute whereby the latter is moved under the shuttle box when the rock shaft is moved in one direction, and a thread hook on the under side of the shuttle box, said thread hook and bobbin chute being constructed and arranged to cause a filling end extending from the shuttle downwardly past the bobbin chute to be engaged by the bobbin chute and positively carried to the mouth of the thread hook to be

engaged thereby as the bobbin chute returns to normal position.

5. An automatic loom having, in combination, a lay, a shuttle, a thread hook on the lay, and a tilting bobbin chute cooperating with the hook to carry a filling end extending from the shuttle down past the bobbin chute to the mouth of the thread hook to be positively engaged thereby.

JONAS NORTHRUP.
